ENDURANCE TESTING MACHINE FOR SPRINGS

Friedrich Wunderlich, Stuttgart, Germany, assignor to Robert Bosch Gesellschaft mit beschränkter Haftung, Stuttgart, Germany

Application July 1, 1938, Serial No. 217,057
In Germany July 16, 1937

7 Claims. (Cl. 73—51)

The present invention relates to fatigue or endurance testing machines for springs, of the type wherein a plurality of springs which are to be tested at the same time are stretched between beams which are movable relative to each other.

The purpose of the invention is to produce an endurance testing machine of this type which makes it possible, by corresponding loading of a plurality of springs of identical kind which are stretched at the same time, to determine in a single continuous test the so-called Wöhler curves for changing load. According to the invention, this is substantially achieved by the fact that the two beams, which are parallel to each other when in the inoperative position, approach each other on their throw movement in such a way that with the springs, which are arranged in rows, the stresses of the individual springs within a row are different from spring to spring corresponding to the different throw of the individual points of the beams.

The invention is more particularly described with reference to the accompanying drawing, in which:

Figure 1 is a diagrammatic arrangement of the subject of the invention.

Figure 2 is a side elevation of a modified form of construction, and

Figure 3 is a section on the line III—III in Figure 2.

On a pin 1, which is arranged so as to be stationary, there are rotatably mounted two beams 2, 3 which run roughly parallel to each other when in the inoperative position shown. Springs 5 are inserted in recesses 4 in the beams. To the lower end of the beams 2, 3 are pivotally connected levers 6, 7, which are connected with a crank mechanism 8, 9. As soon as the crank gear is set into motion, for instance by an electric motor, the pair of levers 6, 7 flexes upwards and downwards alternately out of the middle position shown. When this occurs, the beams 2, 3 approach each other and move away from each other and exert a changing strain upon the springs 5. During this procedure, the lowest spring will carry out a larger throw than the other springs, and the top spring is least stressed. By this means, given equal constitution of all the springs, the lowest spring becomes broken more quickly than the others, then follows the next spring, and so on, while it is appropriate so to dimension the springs that the top spring, which is least loaded, does not become broken even after many million

changes of load. Now, it is only necessary to determine after how many changes of load or minutes or hours the separate springs have successively become broken, and by this means the data for drawing up the known Wöhler curves for materials which are submitted to changing stress are obtained directly. Since the springs are generally not manufactured so exactly that one spring always has the same properties as another spring which has been manufactured in exactly the same way, it is suitable, in order that the stray values may not have an unfavourable influence on the result of the examination to construct the beams of such width that several springs are always disposed side by side. For instance, five further springs of the same kind may be stretched in the same way behind each of the springs shown in Figure 1.

In another form of construction according to Figures 2 and 3, two beams or plates 11, 21 which are parallel to each other, are firmly disposed on four stanchions 10. At the left of Figure 2 is shown a pedestal bearing 12, about the pin 13 of which an oscillating beam 14 is set into and fro movement by a crank mechanism 15, 16. The throw of the crank gear, 15, 16 can be adjusted by means of a radially adjustable slide block 17. Spring plates 15a are fitted on the oscillating beam 14. Between the spring plates 15a and recesses 18 in the plates 11 are inserted a number of springs 19, the right hand ones of which are deflected more by the crank mechanism 15, 16 and those on the left are deflected less by the said mechanism. Thus, with this arrangement, the right hand springs 19 will break more quickly than those disposed further to the left.

The spring plates 15a are pivotally connected with the oscillating beam 14 by pins 20. Further, by means of a pin 22 and a rod 23, a pivotal connection is made between the spring plates 15a and a pin 24 which is firmly disposed in the pedestal bearing 12. By this means, there arises a parallelogram guide 13, 14, 15a, 22, 23, 24 which ensures that, on its upward and downward movement by the crank mechanism, the spring plate 15a can never get out of its vertical position. In this way, undesired influences, which might otherwise arise with the crank drive as a result of one of the ends of the springs getting into an oblique position, are avoided. Care should further be taken to ensure that the spacing of the pin 13 from the spring 19 disposed next to it is not too small, so that the

height of the arc described on the oscillation about the pin 13 can be practically neglected.

While the beams 11 and 21 according to Figure 3 are constructed for the use of several rows 5 of springs side by side as comparatively wide plates, the appropriate oscillating beam 14 is not constructed as a uniform plate. The oscillating beam 14 for the separate rows of springs are rather broken up into a number of separate 10 beams 14a, 14b, 14c, etc.; this has the advantage of making it particularly simple to assemble the spring plates 15a.

I declare, that what I claim is:

1. An endurance testing machine for springs, 15 comprising two relatively movable beams between which a plurality of springs to be simultaneously tested are arranged endwise with their ends in contact with said beams at spaced points along said beams whereby said springs will be contracted and expanded by oscillation of one beam relative to the other, said two beams being arranged parallel to each other when in the inoperative position, and means to oscillate said beams in such a way that the stresses on the individual springs are different from spring to spring corresponding to the different throw of different points along the beams.

2. An endurance testing machine for springs, 30 comprising two relatively movable beams between which a plurality of springs to be simultaneously tested are arranged endwise with their ends in contact with said beams at spaced points along said beams whereby said springs will be contracted and expanded by oscillation of one beam relative to the other, said two beams being arranged parallel to each other when in the inoperative position, a stationary bearing in which one of said beams is mounted, and means to oscillate said one beam relatively to the other beam so that the stresses on the individual springs are different from spring to spring corresponding to the different throw of different points along the beams.

3. An endurance testing machine for springs, 35 comprising two fixed beams, an intermediate oscillatable beam between the same, between which fixed and oscillatable beams a plurality of springs to be tested are arranged endwise with their ends in contact with said beams at spaced points along said beams whereby said springs will be contracted and expanded by oscillation of one beam relative to the other, and means to oscillate said oscillatable beam in such a way that the stresses on the springs are different from spring to spring corresponding to the different throw of different points along the beams.

4. An endurance testing machine for springs, 40 comprising two relatively movable beams arranged parallel to each other when in inoperative position, a plurality of movably arranged supporting surfaces on at least one of said beams

adapted to support the ends of springs, arranged between said beams at spaced points along said beams whereby said springs will be contracted and expanded by oscillation of one beam relative to the other, and means to oscillate one of said 5 beams in such a way that the stresses on the individual springs are different from spring to spring corresponding to the different throw of different points along the beams.

5. An endurance testing machine for springs, 10 comprising two relatively movable beams arranged parallel to each other when in inoperative position, a plurality of movably arranged supporting surfaces on at least one of said beams adapted to support the ends of springs, arranged between 15 one of said beams at spaced points along said beams whereby said springs will be contracted and expanded by oscillation of one beam relative to the other, a parallelogram guide connected to said supporting surfaces to keep the same 20 parallel, and means to oscillate one of said beams in such a way that the stresses on the individual springs are different from spring to spring corresponding to the different throw of different points along the beams.

6. An endurance testing machine for springs, 25 comprising two relatively movable beams, between which a plurality of springs to be simultaneously tested are arranged endwise with their ends in contact with said beams at spaced points 30 along said beams whereby said springs will be contracted and expanded by oscillation of one beam relative to the other, said two beams being of such a width that several rows of springs can be arranged side by side and being arranged 35 parallel to each other when in the inoperative position, and means to oscillate one of said beams in such a way that the stresses on the individual springs are different from spring to spring corresponding to the different throw of different 40 points along the beams.

7. An endurance testing machine for springs, 45 comprising two relatively movable beams between which a plurality of springs to be simultaneously tested are arranged endwise with their ends in contact with said beams at spaced points 50 along said beams whereby said springs will be contracted and expanded by oscillation of one beam relative to the other, said two beams being arranged parallel to each other when in the inoperative position, one of said beams comprising a comparatively wide plate and the other of said beams being divided into a plurality of connected beam portions which are moved jointly, and means to oscillate one of said beams relatively to 55 the other in such a way that the stresses on the individual springs are different from spring to spring corresponding to the different throw of different points along the beams.

FRIEDRICH WUNDERLICH.
